BAG MAKING MACHINE

August F. Beckmann, Narberth, Pa., assignor to
 Benj. C. Betner Company, Devon, Pa., a corporation of Pennsylvania

Application June 23, 1932, Serial No. 618,957

1 Claim. (Cl. 164—99)

This invention relates to new and useful improvements in bag machines and more particularly to machines for manufacturing bags of the so-called satchel or self-opening satchel type.

5 The principal object of the invention is to provide a bag machine of the character set forth wherein the successive bag stock lengths are cut from the stock on a straight, smooth line transversely of the direction of travel of the stock.

10 Another object of the invention is to provide a bag machine as set forth having novel means forming an opening in the stock to permit the severed bag stock lengths to be gripped and carried into finishing mechanism of the machine.

15 Another object of the invention is to provide a machine of the stated character having novel punch means associated therewith for forming a circular opening at predetermined intervals in the advancing stock in the machine.

20 A more specific object of the invention is to provide a machine of the stated character having a transversely positioned straight cutting edge and novel punch means cooperating therewith in timed relation in order that the successive bag stock lengths will be cut from the fed stock on a transverse line coincident with the diameter of each of the circular openings formed in the web.

25 Other features and details of the invention are set forth hereinafter and shown in the accompanying drawing, in which:

30 Figure 1 is a diagrammatic view in perspective showing the paper web traveling through a portion of the machine and the relation of the novel features of the invention with respect thereto;

35 Fig. 2 is an enlarged fragmentary section showing the punch means for forming the apertures in the traveling web;

40 Fig. 3 is an enlarged fragmentary view in section showing the cutter and the relation thereof to the traveling bag stock passing intermediate said cutter and an abutting roller; and

45 Fig. 4 is an enlarged fragmentary view in perspective showing the forward end of a bag section, subsequent to the punching and cutting thereof in accordance with the present invention.

50 Heretofore, in the manufacture of bags of the present character, it has been necessary that the successive bag stock sections be severed from the advancing web in such a manner as to provide a segmental flap or tab on the bottom side for the purpose of providing a projection which may be gripped by a carrier or finger and carried into the finishing stages of the machine.

55 The provision of this projecting segment or tab

gave rise to a substantial waste of material in the manufacture of a number of bags and also made the handling thereof difficult in the finishing stages of the machine for forming the bottom of bags particularly of the satchel type where a substantial arcuate segment was cut from the back end of the stock length to provide for the projecting tab of the forward end of the succeeding bag length.

5 By the present invention, the individual bag lengths are cut from the advancing web on a straight line transverse with respect to the direction of travel of the web which eliminates difficulties encountered in the manufacture of bags heretofore as stated above. The present manner of cutting the individual bag lengths on a straight line transversely to the direction of travel of the web, has been attempted in innumerable instances heretofore, but has been found

10 wholly impractical, because there was no structure which would permit the usual automatic finger to grip only the bottom side of the bag length and carry the bag in that manner into the remaining stages of the machine. The present invention contemplates the provision of novel 15 punch means associated with the machine for forming circular openings in the traveling web at predetermined intervals. The aforementioned punch means and rotary cutting tool, operate in 20 timed relation with each other and are so positioned in the machine that each cut made by the tool occurs coincident with the diameter of each 25 opening formed in the web by said punch means. As shown in Figs. 1 and 4, by cutting or punching 30 the paper web in the manner set forth above, the 35 forward end of each individual bag length is provided with a semi-circular notch in the upper side thereof, which permits the usual finger to engage or grip the lower side of the bag section and advance it to the next stage of manufacture.

40 Referring now more particularly to the drawing, the present invention is shown as applied to the customary machine used in the manufacture of bags of the satchel type, wherein a web 1 is continuously fed from a roll of stock and passes 45 inwardly of the machine about a group of rollers 2 then downwardly about a large roller and through a former (not shown) which forms a substantially flat tubular bag stock as shown in Figs. 1 and 4. The customary paste pot 5 is provided and a narrow disk roller 6, operating therein, contacts with one surface of the advancing web 1 adjacent the edge thereof, to apply the necessary paste thereto for joining the overlapping edges of the tube 4.

In the present instance, as the web 1 is fed from a stock roll, it passes intermediate a pair of shafts 7 and 8 respectively. The web 1 rides on a roller 9 which is rigidly mounted on the shaft 8 5 and a circular cutting element 10 is rigidly mounted on the shaft 7, the said element 10 being provided with a projecting annular beveled portion 11 terminating at its outer end in a cutting edge 12 which is arranged to engage the web 1 and cut 10 a circular opening 13 therein against the abutting surface of the roller 9.

The shafts 7 and 8 respectively, are driven in geared relation with respect to each other by means of gears 21 and 2, as shown in Fig. 1 which 15 are connected by means of other gears, (not shown) to the main drive mechanism of the machine.

A cylindrical bore 15 extends diametrically through the element 10 and the shaft 7 as shown 20 in Fig. 2 of the drawing. A cylindrical plunger 14 is mounted in the bore 15 and extends normally beyond the cutting edge 12 of the annular cutter 11, the said plunger 14 being arranged to be depressed inwardly of the diametrical bore by contact 25 with the roller 9 against the action of a spring 16. The spring 16 acts between the flanged base 17 of the plunger 14 and a plug 18 threaded in the member 10. The outward movement of the plunger 14 is restricted by the outer edge of the flange 17 which engages the annular shoulder 19 formed at the inner end of the plunger bore 15.

When the cutting edge 12 engages the web 1 against the body of the roller 9 and forms the circular opening 13 therein, further rotation of 35 the roller 9 and the element 10 in the directions of the arrows in Fig. 2 causes the spring 16 to actuate the plunger 14 outwardly of the bore 15 to discharge the circular cut-out from the web.

In the present instance a funnel or tube 20 is 40 disposed in alignment with the cutting tool 11 directly above the roller 9 and is provided with a suction force therein for the purpose of aiding the plunger 14 in removing the cut-out from the web 1, the said cut-out passing inwardly of the tube or funnel 20 by virtue of the suction and is discharged in a waste receptacle.

A straight edged cutting tool 23 is mounted on a shaft 24 and arranged for rotation therewith, the said cutting edge residing in longitudinal 45 alignment with said shaft 24 and transversely of the tubular bag stock 4. The tool 23 and shaft 24 are suitably positioned in the machine and driven in timed relation with the feed of the web so that successive individual lengths of the tubu-

lar stock of a predetermined length may be cut from the advancing stock. The individual bag lengths are cut from the stock by means of the tool 23 which engages the material against the body of the roller 25 which is rigidly mounted on a shaft 26.

In order that the cutting of the individual bag lengths from the stock may be on a line substantially coincident with the diameter of an opening 13, it is necessary that the cutting means 10 forming said openings be suitably positioned on the shaft 7 with respect to the web 1 and it is essential, furthermore, that the speed of operation of the cutting means 10 be in accurate timed relation with the speed of rotation of the straight edged cutter 23 and the speed of the traveling web of stock.

The formation of the semi-circular notch in the upper side of the tubular bag lengths permits the finger to grip the bottom side of the section and 20 carry it into the final stages of the machine, thus making practical the straight edge cutting of the bag sections from the stock.

It should be noted that the invention herein set forth may be applied to bag machines of 25 numerous types and is not intended to be limited to paper bags but may be applicable to the manufacture of bags of "cellophane" and other similar material and any combinations of these materials as may be desired in the composition of 30 the bag.

While I have set forth the embodiment of my invention for the purpose of description, it is intended that certain modifications and changes 35 may be incorporated therein within the scope of the appended claim.

What is claimed is:

In a machine, the combination of a roller adjacent one side of a traveling web, a shaft adjacent the other side of said web, the said shaft having a bore diametrically therethrough and being driven in timed relation with said roller, a cutter mounted on the shaft and arranged for rotation therewith, the said cutter having a diametrical bore 40 therein, arranged in alignment with the bore in said shaft, a cutting edge adjacent the outer end of said bore and arranged to contact with the web against the body of the roller forming an aperture therein, a plunger in said bore arranged to project the cut-out portion defined by the cutting edge from the web, and suction means for carrying the cut out portion outwardly of the machine.

AUGUST F. BECKMANN.
